UNITED STATES PATENT OFFICE.

EDWARD A. RYON, OF WELLSBORO, PENNSYLVANIA, ASSIGNOR TO WELLSBORO GLASS COMPANY, OF WILMINGTON, DELAWARE, A CORPORATION OF DELAWARE.

GLASS-GRINDING MACHINE.

1,251,115.

Specification of Letters Patent. Patented Dec. 25, 1917.

Application filed November 24, 1915. Serial No. 63,200.

To all whom it may concern:

Be it known that I, EDWARD A. RYON, a citizen of the United States of America, and a resident of Wellsboro, Tioga county, 5 and State of Pennsylvania, have invented certain new and useful Improvements in Glass-Grinding Machines, of which the following is a specification, reference being had to the accompanying drawings, forming 10 a part thereof.

My invention relates to machines for grinding glass tumblers, bowls and the like, for the purpose of decorating them to enhance their beauty and increase their value.

15 In my copending application Serial No. 859,768 I have shown and described a machine of the same character in general, as that to which my present invention pertains.

20 One object of my present invention is to provide an improved machine of the character and for the purpose above indicated.

Another object is to provide an improved means for holding the glass tumbler, bowl 25 or the like, in position while it is being ground.

Another object is to provide an improved stop mechanism which shall determine with great accuracy the depth of the cut and 30 avoid the possibility of making the cut too deep and spoiling the article which is being decorated.

Still another object is to provide simple and effective means for adjusting the height 35 of the grinding wheel for the purpose of adapting the machine to glass articles of varying sizes.

Another object is to provide such an arrangement of parts as to make the action 40 of the machine positive and accurate, with a view to increasing the speed at which the machine may be operated and enlarging its capacity.

Other objects and advantages of my invention will be set forth hereinafter, and in order that my invention may be thoroughly understood I will now proceed to describe the same in the following specification and then point out the novel features thereof 50 in appended claims.

Referring to the drawings:

Figure 1 is a sectional elevation, in a longitudinal plane, of a machine embodying my invention, and constructed in accordance therewith.

Fig. 2 is an end elevation of the same machine, with certain of the parts broken away.

Figs. 3 and 4 are transverse sectional elevations taken respectively on the lines 3—3 60 and 4—4 of Fig. 1.

The feed mechanism is shown more in detail, in Fig. 5, which is a partial plan view of the central part of the machine, drawn to a larger scale.

Fig. 6 shows a detail view, drawn to a larger scale, of the mechanism for turning on its axis the carrier or holder on which the glass is mounted.

Fig. 7 is an enlarged detail view of the 70 mechanism for turning the carriage which supports the holder, about the main spindle of the machine as an axis.

Fig. 8 illustrates, on a glass or tumbler, a simple design which may be readily produced by the machine of the previous figures.

Referring to Figs. 1 to 7 inclusive, the machine here shown comprises a base or frame 10 which is adapted to be mounted 80 on a bench or other suitable supporting surface 11, a bearing yoke or head-stock 12, a carrier 13, a holder 14 mounted on the carrier, and a grinding wheel 15.

Base or frame.

The base 10 is preferably a flat casting having a slightly elevated flat surface 16 on which the head-stock 12 is mounted, and a low, flat surface 17 on which the 90 grinding wheel bracket 18 is supported. A bracket 19 on which a U-shaped lever 20 is pivoted is also mounted on the base. The use of this link will be hereinafter explained. The elevated portion of the base 95 is hollow and is perforated as shown at 21, to permit one arm of the lever 20 to extend freely through the base as clearly shown in Fig. 1.

Grinding wheel.

The grinding wheel is supported in suitable bearings 22 provided in the bracket 18 and this bracket is mounted on the base 10 in such a way that it can be adjusted vertically to raise and lower the grinding wheel. This adjustment may be effected in any suitable manner;—for example, wedge blocks 23 and 24 may be mounted in a recess 25 in the base and adjusted by one or 110

more adjusting screws 26, each of the screws being cut with left and right-hand threads near its respective ends to engage tapped holes in the wedge blocks in a well-known manner.

Head-stock.

The head-stock has the general form of a yoke with a forward spindle bearing 27 and 10 a rear spindle bearing 28. A bracket or post 29 supports the bearing 27 and a bracket 30 supports the bearing 28, side webs 31 being arranged to interconnect the brackets and tie the structure together. The rear 15 bracket 30 in addition to the bearing 28, is formed to provide a sleeve 32 in which a hollow driving shaft 33 is mounted.

A thimble 34 is mounted to rotate in the bearing 28. Mounted in the bearing 27 is 20 a spindle 35 which has an enlargement 36 constituting a shoulder to limit its longitudinal movement in one direction. It has another enlargement 37 on the opposite end of the bearing but materially spaced therefrom, a spring 38 being interposed between the enlargement 37 and the adjacent end of the bearing to normally hold the spindle at one limit of its longitudinal movement.

The rear end of the spindle extends into 30 the thimble 34 and is splined to it by a Woodruff key 39. Some other suitable means for causing the shaft and thimble to turn together, without interfering with the longitudinal movement of the shaft, may be 35 employed.

The thimble 34 has a stud projection 40 which extends rearwardly beyond the bearing 28 and carries a notched wheel 41 and a gear wheel 42. Both of these wheels are 40 keyed to the stud projection and are held in position by a nut 43.

A latch 44 is pivotally mounted at 45 on the bracket 30 and is adapted to engage one of the notches 46 of the notched wheel 41. 45 The latch is pressed into engagement with the periphery of the wheel by a spring 47.

Keyed to the driving shaft 33 is a mutilated gear 48 which is arranged to mesh with the gear wheel 42. A releasing pawl 50 49 extends laterally from the mutilated gear 48 and is arranged to engage a projection 50 of the latch 44, the arrangement of parts being such that for each revolution of the gear 48 the latch 44 is released by the pawl 55 49 in opposition to the spring 47. The notched wheel 41 and the thimble and spindle are thus rendered free to rotate.

Mounted on the shaft 33 adjacent to the mutilated gear 48, is a driving sheave 51 60 which may be connected by a belt 52 to a motor or other suitable driving means (not shown). The sheave 51 is free to rotate on the shaft 33 except when a clutch ring 53 is set. This is accomplished by a bell crank 65 lever 54 pivoted at 55 which is connected to

the ring by a rod 56 extending through the hollow shaft 33. Each of the positions to which the bell crank lever 54 may be adjusted, is accentuated by a spring 57, having a plurality of depressions to engage a tooth 58 of the lever and hold it in place until it is forcibly moved to another position.

At the opposite end of the bearing 32 from the mutilated gear 48 and the sheave 51, are a pair of mutilated gears 59 and 60. The gear 59 co-operates with a gear wheel 61 on a cam 62. The gear 60 meshes with a pinion or idler 63 which is mounted on a stud 64 affixed to the bracket 30. The idler meshes with a gear wheel 65 which is also secured to the cam 62.

The arrangement of gears 59, 60, 61, 63 and 65 is such that the cam 64 is driven through a predetermined arc first in one direction and then in the other, the gears 59 85 and 61 serving to drive it in one direction and the gears 60 and 65 which are connected by the idler 63 serving to turn it in the opposite direction.

Cam.

The cam 62 is rotatively mounted on the spindle 35 and is spaced from a collar 66 of the thimble 34 by a frictionless thrust bearing 67. The opposite end of the cam 95 has a beveled surface 68 (see Fig. 5) which co-operates with a corresponding beveled surface 69 on one section 70 of a thrust block. This thrust block is held against rotation by a stationary key or spline 71 100 mounted on webs 71^a, but is free to slide longitudinally on the spindle. It has a second section 72, the two sections having co-operating jaws 70^a and 72^a and being interconnected by two pair of toggle links 73 105 (see Figs. 1 and 5). The block section 72 is spaced from the enlargement 37 in the spindle by a frictionless bearing 74 and the arrangement of parts is such that when the links 73 are set a rotation of the cam 62, 110 pushes the spindle forward in opposition to the spring 38.

The toggle links 73 are connected by a yoke 75 and a turn buckle link 76 to a lever 77. This lever is T-shaped and is pivoted at 115 78, the turn buckle being pivotally connected to the bottom of the T as shown in Fig. 1. One arm of the T is adapted to engage an adjustable stop 79 when the toggle links 73 are slightly overset. The opposite 120 arm of the T is pressed outwardly by a spring 80 which must be momentarily compressed in breaking the toggle. This spring tends to hold the T-shaped lever against the stop 79 and prevents the accidental breaking 125 of the toggle, while it does not in any way interfere with the automatic breaking of the toggle but rather tends to facilitate this action, as hereinafter explained.

One end of the U-shaped lever 20 is con- 130

nected to the T-shaped lever 77 between the turn buckle and the stationary pivot 78. This U-shaped lever is pivotally mounted at 81 on the bracket 19 and has an extension 5 or feeler 82 which is adapted to be engaged by the glass article and serves to trip the toggle, when the grinding wheel has made a cut of the desired depth in the glass.

Carrier.

10 The carrier comprises an angle bracket 85 which is secured to the end of the spindle 35 and provides a spherical bearing 86 for a flattened sphere 87 in which a hollow shaft 15 88 of the holder is mounted. The arrangement of parts is such that the center line of the hollow shaft 88 is substantially perpendicular to the center line of the spindle 35. The hollow shaft extends materially above 20 the bearing 86 and is counterbored to provide a cylinder 89 as clearly shown in Fig. 1. A pair of disk supports 90 and 91 are mounted on the hollow shaft 88 and have washers or gaskets 92 which are adapted to engage 25 the inner surfaces and seal the opening of a glass or tumbler when it is mounted on the holder as indicated in Fig. 1. Operating in the cylinder 89 is a piston or plunger 93 which is connected by a rod 94 to a lever 95. 30 This lever is pivoted at 96 on the bracket 85 and is adapted to be actuated by a bell crank lever 97 to which it is connected by a link 98. The bell crank lever 97 is pivoted at 99 on an extension 100 of the bracket 85 and is in a 35 convenient position to be set by the hand of the operator. It is adapted to be so actuated as to impart an inward movement to the piston or plunger 93 in the cylinder 89, thereby creating a partial vacuum in the 40 chamber of the glass or tumbler which is closed by the supporting disks. Thus external air pressure serves to hold the glass or tumbler in position.

45 Mounted on the hollow shaft 88 below the bearing 86 is a notched wheel 101 which is adapted to be engaged by a latch 102. A spring 103 presses the latch 102 into engagement with the periphery of the wheel which is notched to receive it.

50 Adjacent to the notched wheel 101 on the hollow shaft 88 is a bevel gear 104 which meshes with a gear 105 on a countershaft 106. This countershaft is supported in bearings 107 in the bracket 85 and has secured to 55 it near its opposite end, a gear wheel 108.

60 A stationary gear segment 110 is secured to the head-stock 12 by a bolt 111 and has a pawl 112. When the spindle 35 is rotated the carrier 13 is swung about the spindle as 65 an axis thereby producing a certain rotative movement of the hollow shaft 88 by reason of the engagement of the gear wheel 108 with a stationary gear member 110. Furthermore, a projection 113 of the latch 102 is adapted to be engaged by the pawl 112

which is arranged to release the latch 102 from the notch in the wheel 101 with which it is in engagement. The arrangement of parts is such that the notched wheel 101 which holds the shaft 88 in position, is released just before the gear wheel 108 engages the stationary gear segment 110. Thus, a turning movement of the counter-shaft 106 and of the shaft 88 is permitted.

Operation.

The operation of the machine is as follows:—Assuming that the glass or tumbler is mounted in place and that the parts of the machine occupy substantially the positions shown in Fig. 1,—if the clutch lever 54 is set, motion will be transmitted from the driving sheave 51 to the mutilated gears 48, 59 and 60. The first action of the gear wheels 59 and 60 is to produce a rotative 85 over-and-back or an oscillatory movement of the cam 62. This movement forces the block section 70 away from the cam, the motion being transmitted through the toggle links 73 to the block section 72 and then to the 90 spindle 35 which is forced longitudinally and carries the glass against the grinding wheel.

This motion continues until the grinding wheel reaches a predetermined depth at 95 which the finger 82 engages the surface of the glass adjacent to the wheel. As soon as the glass presses against the finger the lever 20 is rocked which in turn causes an oscillation of the lever 77. This oscillation is in 100 opposition to the spring 80 and pushes upwardly on the turn buckle link 76, breaking the toggle joints formed between the links 73. The spring 38 instantly retracts the 105 spindle 35.

In this way one cut, such as the cut 120, Fig. 8, is produced. This action occurs in a very short space of time so that the backward oscillation of the cam 62 does not occur until after the spindle has been retracted by 110 the spring 38. Hence the toggles 73 are reset by the spring 80 pressing on the lever 77 as soon as this is permitted by the return of the cam to the position shown in Fig. 1.

The next action is the tripping of the 115 latch 44 by the pawl 49 of the gear 48. This latch, which has engaged one of the notches of the wheel 41 and has held the spindle against rotation, is now released, and the spindle is free to be turned by the 120 teeth of the mutilated gear 48 which now engage the teeth of the gear wheel 42. The arrangement of parts is such that the spindle is turned through a predetermined angle which depends upon the number of radial 125 cuts (such as 120, Fig. 8) to be formed in a single figure of the design. If there are four as shown, the angle of rotation will be 90°. The latch 44 now enters the next notch 46 of the wheel 41 and the spindle 130

is advanced to make another cut as before. This action continues until finally just as the spindle completes a revolution all of the cuts of a single figure having been made, 5 the pawl 113 engages the stationary pawl 112 and releases the latch 102. Immediately thereafter, the gear wheel 108 comes into engagement with the stationary gear segment 110 and is turned through a predetermined angle sufficient to move the hollow shaft 88 through an angle, say, of 45°, depending upon the spacing, about the circumference of the tumbler, of the several figures of the design.

15 The latch 102 falls into the next notch of the wheel 101 and locks the holder in its new position. The action of the mechanism in producing a second figure of the design is the same as already explained, 20 and the holder is not again turned on its axis until the spindle has made another complete revolution and the second figure is completed.

In like manner, the series of figures is 25 finally completed and the operator stops the machine by pressing downwardly on the clutch lever 54. The special block or bearing 87 is provided for the purpose of permitting the ready manipulation of the 30 holder, it being only necessary to release the binding screws which clamp the sphere in order to swing the holder as desired.

It is obvious that the design may be very 35 materially changed by varying the number of cuts in each figure and by varying the spacing of the figures. These variations may be effected by gear changing,—for example, changing the notching of the wheels 41 and 101, the mutilated gears being adapted 40 accordingly.

Structural variations may be effected 45 within the spirit and scope of my invention, and I intend that only such limitations be imposed as are indicated in the appended claims.

What I claim is:

1. A glass grinding machine comprising a spindle, a carrier affixed thereto, a grinding wheel, and a cam mounted on the spindle and co-axial therewith, and means for oscillating the cam to advance the spindle and the carrier.

2. A glass grinding machine comprising a rotatable spindle, a carrier secured thereto, a grinding wheel, and a cam rotatively mounted on the spindle and adapted to produce a longitudinal movement thereof, and two sets of gears adapted to produce an oscillatory movement of the cam.

60 3. A glass grinding machine comprising a spindle having a collar or enlargement, a carrier secured to the spindle, an actuating block slidably mounted on the spindle adjacent to said collar or enlargement, and a cam rotatively mounted on the spindle ad-

jacent to the actuating block and adapted to coöperate therewith, and means for producing an oscillatory movement of the cam.

4. A glass grinding machine comprising a spindle having a collar or enlargement, 70 a carrier secured to the spindle, an actuating block slidably mounted on the spindle adjacent to said collar or enlargement, and a cam rotatively mounted on the spindle adjacent to the actuating block and adapted to coöperate therewith, and two sets of mutilated gears for producing an oscillatory movement of the cam.

5. A glass grinding machine comprising a spindle having a collar, a bearing in the 80 spindle near one end, a thrust surface adapted to engage the bearing, a spring interposed between the bearing and the collar tending to hold the thrust surface against the bearing, a carrier secured to the spindle, 85 an actuating block comprising two sections, and toggle links interconnecting the sections, a cam rotatively mounted on the spindle and coöoperating with the actuating block, and means for oscillating the cam to advance the 90 spindle, said toggle links being adapted to have their joints broken to permit the retraction of the spindle.

6. A glass grinding machine comprising a 95 spindle, means for limiting the longitudinal movement of the spindle in one direction, a spring tending to hold the spindle against said limiting means, a collar, an actuating block adjacent to the collar composed of two 100 sections, and toggle links connecting the sections, and a cam mounted on the spindle and adapted to coöperate with the actuating block, mutilated gears adapted to oscillate the cam, and means tending to hold the toggle links in a set position, whereby the 105 oscillatory movement of the cam produces a longitudinal movement of the spindle in opposition to the spring.

7. A glass grinding machine comprising a 110 spindle, means for limiting the longitudinal movement of the spindle in one direction, a spring tending to hold the spindle against said limiting means, a collar, an actuating block adjacent to the collar composed of two 115 sections, and toggle links connecting the sections, an annular cam mounted on the spindle and adapted to coöperate with the actuating block, mutilated gears adapted to oscillate the cam, means tending to hold the toggle links in a set position, whereby the 120 oscillatory movement of the cam produces a longitudinal movement of the spindle in opposition to the spring, a grinding wheel, and means adapted to be tripped by the work when the cut has reached a predetermined 125 depth, for breaking the joint between the toggle links.

8. A holder for glass grinding machines comprising a tubular support having a restricted opening at one end, disks mounted 130

on the support and having washers or gaskets adapted to fit into the opening in the glass, a plunger mounted in the tubular support and having a rod extending through the 5 restricted opening, and means for adjusting the position of the plunger to create a partial vacuum within the glass.

9. A holder comprising a bracket, a spherical socket, a spherical bearing member ad- 10 justably clamped in said socket, and a sup- porting member rotatively mounted in said spherical bearing.

10. A holder for glass grinding machines comprising means for partitioning off a 15 chamber in the glass, and means for creating a partial vacuum in the chamber.

11. A holder for glass grinding machines comprising a relatively stationary support having a washer or gasket adapted to enter 20 and close off a chamber in the glass, and means for creating a partial vacuum in the chamber.

12. A holder for glass grinding machines comprising a relatively stationary support 25 having a washer or gasket adapted to enter and close off a chamber in the glass, and a plunger and cylinder embodied in the sta- tionary support for creating a partial vac- um in the chamber.

30 13. A glass grinding machine comprising a bearing bracket or head-stock, a spindle, a carrier secured to the spindle, an edge grind- ing wheel, in the vertical plane of the axis, and means for vertically adjusting the grind- 35 ing wheel.

14. A glass grinding machine comprising a bearing bracket or head-stock, a spindle, a carrier secured to the spindle, a grinding wheel, a driving shaft, a driving sheave, a 40 clutch for operatively connecting the sheave to the shaft, mutilated gears for connecting the driving shaft to the spindle, and means dependent upon the driving shaft for pro- ducing the longitudinal movement of the 45 spindle.

15. A glass grinding machine comprising a bearing bracket or head-stock, a spindle, a carrier secured to the spindle, a grinding wheel, a driving shaft, a driving sheave, a 50 clutch operatively connecting the sheave to the shaft, mutilated gears for connecting the driving shaft to the spindle, an oscillatory cam on the spindle adapted to pro- duce a longitudinal movement thereof, and 55 mutilated gears for connecting the driving shaft to the cam.

16. A glass grinding machine comprising a bearing bracket or head-stock, a spindle, a carrier secured to the spindle, a cutting 60 wheel, a driving shaft, a driving sheave, a clutch operatively connecting the sheave to the shaft, mutilated gears for connecting the driving shaft to the spindle, an oscillatory cam on the spindle adapted to produce a 65 longitudinal movement thereof, and two sets

of mutilated gears between the driving shaft and the cam for producing an oscillatory movement thereof.

17. A glass grinding machine comprising a carrier, a spindle, an actuating block 70 mounted on the spindle having two sections, and toggle links connecting the sections, a yoke connected to the toggle joints formed by the links, a lever connected to the yoke, an adjustable stop for limiting the move- 75 ment of the lever in one direction to hold the toggle links in a set position, a spring tending to push the lever against the stop, and a lever adapted to be tripped by the work for actuating the lever to trip the tog- 80 gle links.

18. A glass grinding machine comprising an edge grinding wheel, a work holder move- 85 able substantially in the plane of the wheel, and means for adjusting the grinding wheel in the same plane at right angles to the direction of the work holder movement.

19. A glass grinding machine comprising a grinding wheel, a movable work holder, a wedge block, and an adjusting screw for 90 varying the positions of the blocks to deter- mine the elevation of the grinding wheel.

20. A glass grinding machine comprising a base, a grinding wheel, a supporting bracket or head-stock mounted on the base 95 having a pair of spaced bearings, a thimble rotatively mounted in one of the bearings, a spindle rotatively mounted in the other bearing and extending into the thimble, and means for connecting the spindle to the 100 thimble to permit an independent longitudinal movement of the spindle; and a car- rier secured to the spindle.

21. A glass grinding machine comprising a base, a grinding wheel, a supporting 105 bracket or head-stock mounted on the base having a pair of spaced bearings, a thimble rotatively mounted in one of the bearings, a spindle rotatively mounted in the other bearing and extending into the thimble, 110 means for connecting the spindle to the thimble to permit an independent longitudinal movement of the spindle, and means for moving the spindle longitudinally to ad- vance the work against the grinding wheel. 115

22. A glass grinding machine comprising a base, a grinding wheel, a supporting bracket or head-stock mounted on the base having a pair of spaced bearings, a thimble rotatively mounted in one of the bearings, 120 a spindle rotatively mounted in the other bearing and extending into the thimble, means for connecting the spindle to the thimble to permit an independent longitudinal movement of the spindle, a carrier se- 125 cured to the spindle at one end adjacent to the grinding wheel, means mounted on the spindle between the bearings for moving the spindle longitudinally, a notched disk se- cured to the thimble, a latch coöperating 130

with the notched disk for holding the thimble and spindle against rotation, and means for releasing the latch and effecting a rotative movement of the thimble and spindle.

5 23. A glass grinding machine comprising a base, a grinding wheel, a supporting bracket or head-stock mounted on the base having a pair of spaced bearings, a thimble rotatively mounted in one of the bearings, 10 a spindle rotatively mounted in the other bearing and extending into the thimble, means for connecting the spindle to the thimble to permit an independent longitudinal movement of the spindle, a carrier 15 secured to the spindle at one end adjacent to the grinding wheel, an annular cam rotatively mounted on the spindle between the bearings, a relatively stationary actuating block surrounding the spindle and adapted 20 to coöperate with the cam in producing the longitudinal movement of the spindle, a notched disk secured to the thimble, a latch coöperating with the notched disk for holding the thimble and spindle against rotation, and means for releasing the latch and 25 effecting a rotative movement of the thimble and spindle.

24. A glass grinding machine comprising a base, a grinding wheel, a supporting 30 bracket or head-stock mounted on the base having a pair of spaced bearings, a thimble rotatively mounted in one of the bearings, a spindle rotatively mounted in the other bearing and extending into the thimble, 35 means for connecting the spindle to the thimble to permit an independent longitudinal movement of the spindle, a carrier secured to the spindle at one end adjacent to the grinding wheel, an actuating block 40 comprising two sections mounted on the spindle and toggle links interconnecting the sections, means for preventing the rotation of the actuating block, a cam rotatively mounted on the spindle and coöperating with 45 the actuating block to produce longitudinal movement of the spindle, means for oscillating the cam to advance the spindle, and means dependent upon the work for breaking the toggle link joints.

50 25. A glass grinding machine comprising a base, a grinding wheel, a supporting bracket or head-stock mounted on the base and having a pair of spaced bearings, a thimble rotatively mounted in one of the 55 bearings, a spindle rotatively mounted in the other bearing and extending into the thimble, a spline for preventing the relative rotation between the spindle and thimble without interfering with the longitudinal movement of the spindle, a carrier secured to the 60 spindle at one end, a spring tending to move the spindle toward the thimble, an actuating block composed of two sections mounted on the spindle and connected by two pairs of 65 toggle links, a cam mounted on the spindle

and adapted to coöperate with the block in producing a longitudinal movement of the spindle in opposition to the spring, and means dependent upon the work for breaking the toggle link joints to permit the retraction of the spindle independently of the cam.

70 26. A glass grinding machine comprising a base, a grinding wheel, a supporting bracket or head-stock mounted on the base 75 and having a pair of spaced bearings, a thimble rotatively mounted in one of the bearings, a spindle rotatively mounted in the other bearing and extending into the thimble, a spline for preventing the relative rotation between the spindle and thimble without interfering with the longitudinal movement of the spindle, a carrier secured to the spindle at one end, a spring tending to move the spindle toward the thimble, an actuating 80 block composed of two sections mounted on the spindle and connected by two pairs of toggle links, a cam mounted on the spindle and adapted to coöperate with the block in producing a longitudinal movement 85 of the spindle in opposition to the spring, a yoke interconnecting the toggle links, a lever connected to the yoke, an adjustable stop for limiting the movement of the lever to hold the toggle links in a set position, a spring tending to push the lever against the stop, and means dependent upon the work for actuating the lever in opposition to the spring to break the toggle link joints; and means dependent upon the work for breaking the toggle link joints to permit the retraction of the spindle independently of the cam.

90 27. A glass grinding machine comprising a base, a grinding wheel, a supporting 105 bracket or head-stock mounted on the base and having a pair of spaced bearings, a thimble rotatively mounted in one of the bearings, a spindle rotatively mounted in the other bearing and extending into the thimble, a spline for preventing the relative rotation between the spindle and thimble without interfering with the longitudinal movement of the spindle, a carrier secured to the 110 spindle at one end, a spring tending to move the spindle toward the thimble, an actuating block composed of two sections mounted on the spindle and connected by two pairs of 115 toggle links, a cam mounted on the spindle and adapted to coöperate with the block in producing a longitudinal movement of the spindle in opposition to the spring, a yoke interconnecting the toggle links, a lever connected to the yoke, an adjustable stop for limiting the movement of the lever to hold the toggle links in a set position, a spring tending to push the lever against the stop, means dependent upon the work for actuating 120 the lever in opposition to the spring to break the toggle link joints, and a lever piv- 125

totally connected to the first-named lever and having an arm extending adjacent to the grinding surface of the wheel and adapted to be actuated by the work when a cut of a predetermined depth has been made, to break the toggle link joints and permit the quick retraction of the spindle and carrier independently of the cam.

28. A glass grinding machine comprising a base, a grinding wheel, a supporting bracket or head-stock mounted on the base and having a pair of spaced bearings, a spindle rotatively mounted in one of the head-stock bearings, a carrier secured to the spindle, a thimble rotatively mounted in the other head-stock bearing, a shoulder on the spindle adjacent to the head-stock bearing for limiting the longitudinal movement of the spindle in one direction, a collar or enlargement at the opposite end of the bearing, a spring interposed between the bearing and said collar or enlargement for holding the spindle at one limit of its motion, an actuating block mounted on the spindle adjacent to the collar or enlargement, an oscillatory cam mounted on the spindle adjacent to the actuating block, said block comprising two sections and two pairs of toggle links connecting the sections, a driving shaft, mutilated gears for connecting the driving shaft to the thimble and two sets of mutilated gears for connecting the driving shaft to the cam for producing an oscillatory movement of the cam, and a step by step rotative movement of the thimble.

29. A glass grinding machine comprising a base, a grinding wheel, a supporting bracket or head-stock mounted on the base and having a pair of spaced bearings, a spindle rotatively mounted in one of the head-stock bearings, a carrier secured to the spindle, a thimble rotatively mounted in the other head-stock bearing, a shoulder on the spindle adjacent to the head-stock bearing for limiting the longitudinal movement of the spindle in one direction, a collar or enlargement at the opposite end of the bearing, a spring interposed between the bearing and said collar or enlargement for holding the spindle at one limit of its motion, an actuating block mounted on the spindle adjacent to the collar or enlargement, an oscillatory cam mounted on the spindle adjacent to the actuating block, said block comprising two sections and two pairs of toggle links connecting the sections, a driving shaft, mutilated gears for connecting the driving shaft to the thimble and two sets of mutilated gears for connecting the driving shaft to the cam for producing an oscillatory movement of the cam, and a step by step rotative movement of the thimble, said thimble being connected to said spindle by a spline to permit the longitudinal movement of the spindle while preventing rotative movement of the thimble relative to the spindle, a notched wheel secured to the thimble, a latch adapted to engage the notched wheel, a pawl mounted on one of said gears for releasing the latch to permit a step by step movement of the thimble, a carrier secured to the spindle, a work holder mounted on the carrier, and a stop lever adapted to engage the work when it has advanced to produce a cut of a predetermined depth, for breaking the toggle joints and permitting the spindle and carrier to be retracted independently of the cam.

30. A glass grinding machine comprising a base, a grinding wheel, a supporting bracket or head-stock mounted on the base and having a pair of spaced bearings, a spindle rotatively mounted in one of the head-stock bearings, a carrier secured to the spindle, a thimble rotatively mounted in the other head-stock bearing, a shoulder on the spindle adjacent to the head-stock bearing for limiting the longitudinal movement of the spindle in one direction, a collar or enlargement at the opposite end of the bearing, a spring interposed between the bearing and said collar or enlargement for holding the spindle at one limit of its motion, an actuating block mounted on the spindle adjacent to the collar or enlargement, an oscillatory cam mounted on the spindle adjacent to the actuating block, said block comprising two sections and two pairs of toggle links connecting the sections, a driving shaft, mutilated gears for connecting the driving shaft to the thimble and two sets of mutilated gears for connecting the driving shaft to the cam for producing an oscillatory movement of the cam, and a step by step rotative movement of the thimble, said thimble being connected to said spindle by a spline to permit the longitudinal movement of the spindle while preventing rotative movement of the thimble relative to the spindle, a notched wheel secured to the thimble, a latch adapted to engage the notched wheel, a pawl mounted on one of said gears for releasing the latch to permit a step by step movement of the thimble, a carrier secured to the spindle, a work holder mounted on the carrier, and a stop lever adapted to engage the work when it has advanced to produce a cut of a predetermined depth, for breaking the toggle joints and permitting the spindle and carrier to be retracted independently of the cam.

31. A glass grinding machine comprising a spindle, means for limiting the longitudinal movement of the spindle in one direction, a spring tending to hold the spindle against said limiting means, a collar, an actuating block adjacent to the collar composed of two sections and toggle links connecting these sections, means for actuating the connected sections to produce a longitudinal movement of the spindle in opposition to the spring, and means adapted to be tripped by the work when the cut has reached a predetermined length for breaking the joints between the toggle links.

32. A glass grinding machine comprising

ing rotative movement of the thimble relative to the spindle, a notched wheel secured to the thimble, a latch adapted to engage the notched wheel, and a pawl mounted on one of said gears for releasing the latch to permit a step by step movement of the thimble.

30. A glass grinding machine comprising a base, a grinding wheel, a supporting bracket or head-stock mounted on the base and having a pair of spaced bearings, a spindle rotatively mounted in one of the head-stock bearings, a carrier secured to the spindle, a thimble rotatively mounted in the other head-stock bearing, a shoulder on the spindle adjacent to the head-stock bearing for limiting the longitudinal movement of the spindle in one direction, a collar or enlargement at the opposite end of the bearing, a spring interposed between the bearing and said collar or enlargement for holding the spindle at one limit of its motion, an actuating block mounted on the spindle adjacent to the collar or enlargement, an oscillatory cam mounted on the spindle adjacent to the actuating block, said block comprising two sections and two pairs of toggle links connecting the sections, a driving shaft, mutilated gears for connecting the driving shaft to the thimble and two sets of mutilated gears for connecting the driving shaft to the cam for producing an oscillatory movement of the cam, and a step by step rotative movement of the thimble, said thimble being connected to said spindle by a spline to permit the longitudinal movement of the spindle while preventing rotative movement of the thimble relative to the spindle, a notched wheel secured to the thimble, a latch adapted to engage the notched wheel, a pawl mounted on one of said gears for releasing the latch to permit a step by step movement of the thimble, a carrier secured to the spindle, a work holder mounted on the carrier, and a stop lever adapted to engage the work when it has advanced to produce a cut of a predetermined depth, for breaking the toggle joints and permitting the spindle and carrier to be retracted independently of the cam.

31. A glass grinding machine comprising a spindle, means for limiting the longitudinal movement of the spindle in one direction, a spring tending to hold the spindle against said limiting means, a collar, an actuating block adjacent to the collar composed of two sections and toggle links connecting these sections, means for actuating the connected sections to produce a longitudinal movement of the spindle in opposition to the spring, and means adapted to be tripped by the work when the cut has reached a predetermined length for breaking the joints between the toggle links.

32. A glass grinding machine comprising

a spindle, means for limiting the longitudinal movement of the spindle in one direction, a spring tending to hold the spindle against said limiting means, a collar, an actuating block adjacent to the collar composed of two sections and toggle links connecting these sections, a cam adapted to operate with the actuating block, means tending to hold the toggle links in a set position whereby the cam is adapted to produce a longitudinal movement of the spindle in opposition to the spring, and means adapted to be tripped by the work for breaking the joints between the toggle links.

33. A glass grinding machine comprising a spindle, a carrier affixed thereto, a grinding wheel, a rotary cam coaxial with the spindle, and means for oscillating the cam to advance the spindle and the carrier.

34. A glass grinding machine comprising a spindle, a carrier secured to the spindle, an actuating block, a driving shaft, a rotary cam mounted with its axis parallel to the axis of the spindle and adapted to actuate the block to produce a longitudinal movement of the spindle, and means for rotating the spindle.

35. A glass decorating machine comprising a tool, a work carrier adapted to be rotatively adjusted, yielding means for retracting the work carrier, and a rotary cam for moving the carrier axially toward the tool, and means for permitting the retraction of the carrier independently of the cam.

36. A glass decorating machine comprising a work carrier, a tool, an actuator for moving the carrier toward the tool, means for retracting the carrier, collapsible means interposed between the actuator and the carrier, and means for tripping the collapsible means.

37. A glass decorating machine comprising a work carrier, a tool, an actuator for moving the carrier toward the tool, yielding means for retracting the carrier, and collapsible means for permitting the retraction of the carrier independently of the actuator.

38. A glass decorating machine comprising a work carrier, a tool, an actuator for moving the carrier toward the tool, yielding means for retracting the carrier, collapsible means interposed between the actuator and the carrier, and means for tripping the collapsible means to permit the independent retraction of the carrier.

39. A glass decorating machine comprising a work carrier, a tool, an actuator for

moving the carrier toward the tool, yielding means for retracting the carrier, and a quick return mechanism for the carrier dependent upon the depth of the cut.

40. A glass decorating machine comprising a work carrier, a grinder, an actuator for moving the carrier toward the grinder, means for retracting the carrier, collapsible means interposed between the actuator and the carrier, and means dependent upon the depth of the cut for tripping the collapsible means.

41. A glass decorating machine comprising a work carrier, a grinder, an actuator for moving the carrier toward the grinder, means for retracting the carrier, collapsible means interposed between the actuator and the carrier, a finger adjacent to the cutter adapted to be engaged by the work and trip the collapsible means at a predetermined depth of cut.

42. A glass decorating machine comprising a work carrier, a grinder, an actuator for moving the carrier toward the grinder, a spring for retracting the carrier, and collapsible means for permitting the retraction of the carrier independently of the actuator.

43. A glass decorating machine comprising a work carrier, a grinder, an actuator for moving the carrier toward the grinder, a spring for retracting the carrier, collapsible means interposed between the actuator and the carrier, and means for tripping the collapsible means to permit the independent retraction of the carrier.

44. A glass decorating machine comprising a work carrier, a grinder, an actuator for moving the carrier toward the grinder, a spring for retracting the carrier, toggle links interposed between the actuator and the carrier, and means dependent upon the depth of the cut for tripping the toggle to permit the retraction of the carrier independent of the actuator.

45. A glass decorating machine comprising a work carrier, a grinder, an actuator for moving the carrier toward the grinder, a spring for retracting the carrier, toggle links interposed between the actuator and the carrier, a pivoted finger close to the cutter adapted to be engaged by the work at a predetermined depth of cut, and links connecting the finger to the toggle links whereby the toggle links are tripped and the carrier is retracted.

In witness whereof, I have hereunto set my hand this 27 day of October, 1915.

EDWARD A. RYON.
